LIVE FISH HANDLER

Dewitt Taylor, 1509 E. Cold Spring Lane,
Baltimore, Md. 21218

Filed July 22, 1969, Ser. No. 18,319

Term of patent 14 years

Int. Cl. D22—08

U.S. Cl. D22—31

FIG. 1

FIG. 2

FIG. 3

FIG. 1 is a perspective view of a live fish handler incorporating my new design;

FIG. 2 is a front elevation thereof and discloses the outer face of the blade whose inner face is shown in FIG. 1, and

FIG. 3 is a right side elevation thereof taken on the line 3—3 of FIG. 2.

I claim:

The ornamental design of live fish handler, as shown and described.
